ATTORNEY.

UNITED STATES PATENT OFFICE.

JOSEPH W. WOOLLEY, OF COLUMBUS, OHIO.

INTERVIEWER.

Application filed May 26, 1928. Serial No. 280,754.

This invention relates to an interviewer which is capable of a wide range of use but is particularly adapted for use on the doors of apartments.

5 An object of the invention is to provide an interviewer which cannot be removed from the outside of the door so as to allow access to the inside of the door and thereby open the same and also to provide means whereby 10 the closure member of the interviewer can only be opened from the inside of the door.

It is a further object of the invention to provide means whereby the securing means for the interviewer are concealed and thereby 15 add to the attractiveness of the appearance of the interviewer upon both the inside and the outside of the door.

A still further object is to provide means upon the fixed outside member of the interviewer for receiving indicia such as the name of the occupant of the apartment and the apartment number thereby eliminating any necessity for placing any additional devices upon the door.

25 An important object of my invention is to provide means upon the interviewer whereby a caller can attract the attention of the occupants of the apartment thereby avoiding the necessity of separate call bells. The 30 means for attracting the attention of the occupants is disposed so as to add to the attractiveness of the interviewer and also to serve as a bar member upon the outside member of the interviewer thereby further preventing any possibility of access through the 35 interviewer itself to the inside of the door.

It is also my intention to provide means whereby the entire interviewer can be attached to a door which has only a single opening 40 provided therein. This is important since my interviewer can be attached to the door in a minimum of time and also by unskilled labor.

A still further object of the invention is to 45 provide an interviewer which is capable of being used upon the type of doors commonly known as servidores.

With these and other objects in view as will hereinafter appear, my invention consists in 50 the construction, arrangement and combination of the various parts of my device, whereby the objects contemplated are attained, as hereinafter more fully set forth, pointed out in my claims, and illustrated in the accompanying drawings, in which:

Figure 1 is a perspective view of my device taken from the outside of the drawing;

Figure 2 is an elevational view from the inside of the door;

Figure 3 is a vertical sectional view; 60

Figure 4 is a disassembled perspective view;

Figure 5 is a fragmentary perspective view showing the latch, and

Figure 6 is a sectional view on the section 65 line 6—6 of Figure 1.

Figure 7 is a fragmentary sectional view showing the connection between the plates and the door.

In the drawings like reference characters 70 refer to like parts.

My device consists essentially of two plate members 10 and 11. The plate member 10 is placed upon the outside of the door and the plate member 11 is placed upon the inside of 75 the door. These plate members are preferably circular but may be of any desired shape. A portion of the door is indicated at 12 having a circular opening 13 therein.

Plate members 10 and 11 are provided with 80 aligned openings 14 and 15 respectively, the opening 14 being slightly less in diameter than the opening 15 for a purpose to be later described. The plate member 10 has upon the inside surface thereof upstanding lugs 16 which are preferably 4 in number and spaced apart 90 degrees as shown. Each of the lugs 16 has a threaded opening 17 extending into the same from the inside but not going entirely through the same. The plate member 11 is provided with an inwardly extending 85 circular flange 18 which is adapted to overlap the lugs 16 and the flange 18 is recessed to accommodate the lugs 16 and is also provided with apertures 19 in alignment with the threaded openings 17. Bolts 20 extends through the unthreaded openings 19 into the threaded openings 17 of the lugs 16 for securing the plate members 10 and 11 together and securing the same to the periphery of the 90 opening 13 in the door 12. It will be noted that when the plate members 10 and 11 are secured together in this manner it is impossible to secure access to the bolts 20 from the outside of the door.

The plate 11 is provided with an upstanding inwardly extending flange 21 which is provided at the top portion thereof with spaced ears 22 having aligned openings 23 therein. 105

A closure member 24 is provided with spaced ears 25 which are disposed between the ears 22 and which also have aligned openings 26 therein which are adapted to align with the openings 23 in the ears 22 for the reception of a pivot pin 27. A spring 28 encircles the pivot pin and has one end 29 bearing against the plate 11 and the other end 30 bearing against the edge 31 of a shield 32 provided so as to partially enclose the main body of the spring 28. The shield 32 is preferably cast integral with the closure member 24 and its main function is to conceal the spring 28 and also to provide a contact for the end 30 of the spring 28. By this construction the interior appearance of the interviewer is maintained attractive and also eliminates any possibility of the ends of the spring 28 from catching in garments which may accidentally brush against the same.

Opposite to the side upon which the closure member or element 24 is pivoted I provide a slot 33 extending from the periphery part 25 way towards the center of the closure element and upon each side of the slot 33 ears 34 are provided with aligned openings 35 in which a latch member 36 is pivoted. The latch member has an operating handle 37 with the cross bars 38 thereon which span the slot 33 and thereby limit the movement of the latch in one direction while the shoulder 39 limits the movement of the latch in the opposite direction.

The latch is of a peculiar construction shown particularly in Figure 5 and consists of the bolt member 40 having the inclined surface 41 which is adapted to cooperate with the inclined surface 42 provided upon the flange 43 integral with the flange 21 upon the plate member 11. Extending outwardly from the side of the bolt member 40 is a lug 44 having an inclined surface 45 with which one end of a spring 46 is adapted to cooperate while the other end of the spring 46 engages against an ear 34. The spring 46 is wound around the pivot pin 47 which pivots the latch to the ears 34. The latch is maintained by the spring 46 with its bolt 40 in upward position and upon closing the closure 24 the inclined surfaces 42 and 41 will act as cam members to force the bolt 40 downwardly so as to pass the flange 43 and then the spring 46 will automatically raise the bolt 40 into locking position behind the flange 43. It will be seen that the closure member 24 conceals the bolts 20 upon the inside of the door.

The construction of the plate 10 will now be described. At the top side of the plate 10 and upon the inside thereof is provided a recess 48 and a sight opening 49 is provided from the front of the plate communicating with this recess 48. The recess 48 terminates short of the opening 14 providing a shoulder 50. Into this recess a card bearing the

number of the apartment or other information can be placed.

At the bottom of the plate 10 and extending also upon the inside of the plate is a recess 51 having an opening 52 upon the side 70 thereof. In this case also a sight opening 53 is provided which communicates with the recess 51.

In this recess a card bearing the name of the occupant of the apartment can be placed. 75 In regard to both of the recesses 48 and 51 it will be noted that the wall of the door itself is utilized as a backing for the card receiving receptacles thereby eliminating expensive machining of the plate.

The periphery of the opening 14 is thickened at 54 as shown and upon the upper portion of this thickened part 54 two spaced ears 55 are provided having aligned apertures which receive the pivot pin 56 upon which 85 the knocker 57 is pivoted. The knocker arm 58 extends entirely across the opening 14 and serves also as a grille bar dividing the opening in half. Adjacent the hinge point 59 of the knocker 57 a shoulder 60 is provided 90 which limits the movement of the knocker arm away from the plate 10 so as to permit the knocker to serve also as a grille bar. As a general rule it is desired that the arm 58 should only have approximately a 30 degree 95 swing away from the pivot point. If desired a button or handle 61 may be secured to the central point of the arm 58 and can be secured to the arm 58 in any desired manner. The knocker 57 terminates at the end away 100 from the pivot point in a knocking element 62 which can be of any artistic design such as a lion's claw or the like. The knocking element 62 is disposed so as to knock against the metal plate 10. The knocker 57 has a three-fold function in that it adds to the attractiveness of the interviewer, it serves as a means for signalling the occupants of the apartment and finally it serves as a grille bar dividing the opening 14 so as to render it difficult for 105 anyone to insert an arm through the opening or an instrument through the opening 14 to the inside of the door. If desired the knocker arm 58 can have extensions extending away therefrom so as to further divide up the space 110 within the opening 14.

It was noted above that the diameter of the opening 14 was less than the diameter of the opening 15. This is provided for the following purpose:

Whenever the door is of such thickness that the plates 10 and 11 are spaced apart a considerable distance it is necessary to place an element 64 bridging the gap between the plates. For this purpose the slight overlap 125 of the periphery of the opening 14 serves as a shoulder against which one side of the element 64 contacts and the other side of the element 64 fits into the circular recess 65 provided in the closure 24. The element 65 is 130

preferably made of spring metal and various widths are provided to accommodate the different thicknesses of doors. It is merely necessary to spring the element 64 into place after the plates 10 and 11 have been secured together. The element 64 will also have a further function in positively preventing any draft through the closure 24. Where the thickness of the door is small as in some metal doors the element 64 may if desired be dispensed with.

By having the closure member swing upwardly it is possible to use my device with the doors known as servidores since it can be placed upon one side or the other of the thickened central portion of these doors which is not possible with interviewers in which the closure member opens from the side. However, it is to be distinctly understood that the pivot point of the closure member in my device may if desired be placed upon the side or at any other position about the periphery of the plate 11.

The material from which I preferably manufacture the device is a composition zinc alloy which is light in weight, can be easily cast and is malleable and will not crack easily.

The operation and installation of my device is as follows: It is only necessary to drill a single hole 13 in the door. The plate 10 is then placed against the outside of the door and the plate 11 against the inside of the door with the openings 19 in alignment with the threaded openings 17. The bolts 20 are then screwed into place firmly, securing the plates 10 and 11 to the door. The spring element 64 is then sprung into place and the entire device is assembled. Whenever the knocker 57 is knocked against the door the occupant of the apartment need merely unlatch the latch 36, lift the closure member and inspect the caller before opening the door itself. With a device of this type it can be seen that under no circumstances need the door be opened for the entry of suspicious persons. It is also possible to converse with the person outside the door without the necessity of opening the door. As can also be seen, whenever the door is equipped with my device there is no necessity for installing upon the door or adjacent thereto a knocker or indicia carrying devices since everything necessary is embodied in my device.

Some changes may be made in the construction and arrangement of the invention set

forth above, without departing from the real purpose and spirit thereof, and it is the intention to cover by the following claims, any modified form of structure or use of equivalents, which may be reasonably included, 60

within their scope.

I claim:

1. An interviewer comprising plate members secured to a door or the like, a knocker pivoted to one of said plate members and 65 forming also a grille bar and means upon said knocker limiting the movement thereof from said plate member to which the knocker is pivoted.

2. An interviewer comprising inside and 70 outside plate members having aligned apertures therein, a knocker pivoted to said outside plate member, a knocker arm upon said knocker extending across said aligned apertures and serving as a grille bar and means 75 upon said knocker limiting the movement thereof from said plate member to which the knocker is pivoted.

3. An interviewer comprising means secured to the periphery of an opening in a door 80 having an aperture therethrough, means normally closing said aperture, pivoted signalling means connected to said first mentioned means and serving also as a grille bar and means limiting the movement of said signalling means 85 from said door.

4. An interviewer comprising means secured to the periphery of an opening in a door having an aperture therethrough, means normally closing said aperture, pivoted signalling means connected to said first mentioned means and means limiting the extent of the swing of said signalling means from said door so as to permit said signalling means to function as a grille bar. 95

5. An interviewer for a door or the like comprising an outside member, an inside member spaced from said outside member, said members having aligned openings, a closure member mounted upon said inside member for closing said openings, concealed means securing said inside and outside members together so that the outside member cannot be removed from the outside of the door, a pivoted knocker serving as a grille bar upon said outside member for signalling persons upon the inside of the door and a lug disposed upon said knocker for limiting the movement thereof from said door. 100 105

JOSEPH W. WOOLLEY.
